NAIL.

No. 895,846.

Specification of Letters Patent.

Patented Aug. 11, 1908.

Application filed October 19, 1907. Serial No. 398,249.

To all whom it may concern:

Be it known that I, HENRY W. DIERS, a citizen of the United States, residing at Red Wing, in the county of Goodhue and State of Minnesota, have invented a new and useful Nail, of which the following is a specification.

This invention relates generally to nails, and particularly to that class employed in securing felt to roofs, or for attaching sheathing paper to buildings or advertisements to sign boards.

The object of the invention is, in a novel and practical manner, without in any way changing the construction of the nail or of employing solder, to combine an ordinary nail, such as a wire nail, with a cap in such way that not only will the nail be held positively against disconnection with the cap, but the latter will operate in an effective manner to perform the dual function of holding the object to be secured in position, and also of preventing water seeping or passing under the cap to the stem or shank of the nail.

With the above and other objects in view, as will appear as the nature of the invention is better understood, the same consists in the various novel details of construction of the roofing nail, as will be hereinafter fully described and claimed.

In the accompanying drawings, forming a part of this specification, and in which like characters of reference indicate corresponding parts, Figure 1 is a view in perspective displaying a nail in the course of its assembly with the cap. Fig. 2 is a perspective detail view of the finished nail, viewed from the under side thereof. Fig. 3 is a view in longitudinal section, on an enlarged scale, through a nail constructed in accordance with the present invention.

The nail as herein shown is of the ordinary wire type, having a roughened or barbed shank 1, and a flat head 2. This nail is combined with a cap or head designated generally 3, which forms the essential feature of the present invention, as, owing to the novel manner in which it is assembled with the nail, it is held positively against disconnection from the nail, without the employment of solder.

The cap or head is constructed from a strip of sheet metal such as tin and comprises a back member 4, a face member 5 and a locking flange 6, the latter forming a continuation of the face member. The back member 4 is provided at its center with an orifice 7 through which the shank of the nail projects, and when the cap is struck up or formed to shape the metal of the back member around the orifice 7 will be dished inward, as shown at 8. This latter feature, however, is not one of practical importance as if the female die be perfectly flat on its upper surface this depression does not appear. The face member 5 immediately over the head is outward dished as at 9.

In assembling the cap or head with the nail, the former, having been brought to the shape shown in Fig. 1, the nail is inserted through the orifice 7, and by a suitable mechanism, the flange 6 is turned under and against the back member 4 and the perimeter of the head is then dished downward, or toward the point of the nail, as shown at 10, thereby providing a marginal edge 11 which will bite into the felt, paper, or the like and thus preclude the entrance of water around the head of the nail, whereby the latter will be shielded from corrosion.

It will be seen from the foregoing description that although the improvements herein defined are simple in character, they will be thoroughly efficient for the purposes designed, and will result in the provision of a thoroughly effective article of hardware.

Having thus fully described the invention what is claimed is:—

A fastener comprising a cap consisting of a strip of metal folded upon itself and having one end bent around the other end, and a nail having its head disposed between the members of the cap.

In testimony that I claim the foregoing as my own, I have hereto affixed my signature in the presence of two witnesses.

HENRY W. DIERS.
